UNITED STATES PATENT OFFICE

JACOB EDGE, OF DOWNTONTOWN, PENNSYLVANIA, ASSIGNOR, BY MESNE ASSIGNMENTS, TO UNITED STATES GYPSUM COMPANY, OF WILMINGTON, DELAWARE, A CORPORATION OF DELAWARE

ART OF MARKING PLASTIC MATERIAL

Application filed July 12, 1929. Serial No. 377,729.

The present invention relates to the art of marking plastic material, and more particularly to the marking of articles formed from fibrous matter such as wood pulp and similar material. The invention is particularly advantageous for use in connection with the manufacture of relatively thick sheet material such as wall boards or insulating boards. One object of this invention is the provision of suitable mechanism for marking products of this character which will not involve any extensive alteration in machines now being used. Another object of the invention is to provide, as a new article of manufacture, an article having a distinctive marking placed on at least one of the faces thereof. To these and other ends the invention resides in certain improvements and combinations of parts, all as will be herein-
20 after more fully described, the novel features being pointed out in the claims at the end of the specification.

In the drawing:

Fig. 1 is a diagrammatic view of a board forming machine, to which the present invention has been applied;

Fig. 2 is a detail view showing a portion of the felt to which a marking means, formed according to the present embodiment of the invention, has been applied;

Fig. 3 is a view in cross section taken on line 3—3 of Fig. 2; and

Fig. 4 illustrates a portion of pulp board bearing a marking therin in accordance with the present invention.

Similar reference numerals throughout the several views indicate the same parts.

The present embodiment of the invention provides a method and apparatus of the class described which are simple in nature and capable of producing, at a very moderate cost, the desired results of marking the board and at the same time permitting effective control of the manufacturing operation to produce a uniformly high grade of product. The present invention is also particularly advantageous for the reason that no change need be made in present board forming machinery other than a change in the felt or other material which are used in connection

with the mechanism for pressing the newly formed board.

Referring more particularly to the drawing there is shown at 5 in Fig. 1 a cylinder vat which may be of usual construction and in which there is mounted hollow cylinder 6 having the usual form of perforated face for felting the stock which is run into the cylinder vat 5. The board 7, formed on cylinder 6 passes away from the cylinder and between a pair of endless carrying felts 8, 8 which are arranged over rollers 9, 9. Intermediate the rollers 9, 9 there is disposed a plurality of press rolls 10, 10 which may be adjusted toward and from each other in a well known manner. These press rolls function to remove the excess water from the newly formed board and to compress the board to increase its density and decrease its thickness. The mechanism thus far described is of a generally conventional form.

In accordance with the present invention there will be provided on at least one of the felts 8, preferably on the lower felt which engages the back face of the board, one or more raised characters which will be arranged on that face of the felt which is adjacent to the board being formed.

The raised characters on the felt may be formed in various ways but, in the present instance, there is preferably secured to the face of the felt a strong, tough cord, such as for example what is known as chalk line. This cord may be worked into the fabric of the felt, as shown at 11, or it may be laid on the face of the felt and secured thereto by a fine strand of cord or thread as shown at 12. In some instances the characters could be formed by first laying a strand of cord upon the face of the felt and then using the same size cord by working it alternately into the material and over the first mentioned strand or cord with the loops thereof passing closely adjacent each other so as to form the raised character. Obviously this may be done other ways, for example, the cord may be secured in place by metal clips or in some instances may be secured to the felt by a suitable adhesive material. Instead of using cord it is possible to form suitable characters

by using narrow strips of felt which are secured to the felt in the manner above described.

Another manner of forming the raised characters is to apply on the face of the felt a series of strands of thread arranged in the nature of embroidery work. This can be done by the use of embroidering machines of conventional design. An example of this 10 style of character is illustrated at 13 in Fig. 2.

Any number of markings can be disposed upon the felt 8 but, in the present instance, it is preferable to space the individual markings a foot or more apart so that when the 15 board is being used and is cut into smaller pieces, as in the construction of a house, the markings, such as a trade-mark, will appear even on the smaller pieces of board.

It will be readily seen that, after the board 20 is formed and passes into the space between the felts 8, 8, the face of the felt will come in contact with the board and travel along with the board in fixed relation therewith, and the raised characters on the felt will bear 25 against the relatively soft face of the newly formed board and will be imbedded therein, then as the board travels further between the felts and reaches the press rolls 10, 10 a considerable amount of water, which it contains, 30 will be squeezed out and the board will be reduced in thickness and, at the same time, the raised characters on the felt will be more sharply embedded in the board and the material of the board will be closely pressed 35 around the individual strands forming such character. The result is that the board leaves the press part of the machine with sharply formed intaglio markings so that when the board subsequently passes to the 40 dryer the marks will be retained permanently in the face of the board.

It will thus be seen that the present invention provides a very simple method and apparatus for applying markings to plastic 45 pulp articles and, in case of machines for forming articles in the shape of boards, there will not be any alteration needed except what alteration is necessary in the felt which is always a replaceable part of the machine.

50 The present method of markings is not limited in its use to endless felts, as indicated in the drawing, but may be carried out with equal facility by felts which are not endless in form.

55 I claim:

1. A carrying felt for use in board forming machinery, said felt having secured to at least one face thereof a cord arranged to form an intaglio mark in the adjacent face 60 of the newly formed, comparatively soft board.

65 2. A carrying felt for paper making machines having a cord sewed therein so as to present a plurality of adjacent strands disposed on at least one face thereof and adapt-

ed to form an intaglio mark in the adjacent face of the newly formed, comparatively soft web.

3. A carrying felt for board machines, having a cord secured entirely upon the outside of one face thereof by means of a relatively fine strand of thread fastened successively into the felt and around said cord, said cord being firmly secured to the face of the felt and arranged to present a raised character thereon so that pronounced, permanent markings will be formed by said cord in the adjacent face of the newly formed, comparatively soft board web. 75

4. A web-carrying felt for board making machines, the felt having substantial, raised portions formed into designs at intervals on its surface, said raised portions contacting directly with and pressing into the surface of the wet, plastic web carried by the felt 80 to form pronounced, permanent, indented markings in said web. 85

5. In combination in a machine for forming sheets of plastic material, means for forming the plastic material into a web, carrying felts for supporting said web while in a more or less plastic condition, means for compressing said felts and said web to remove excess moisture from the web and densify the web, and means secured on the face of at least one of the felts comprising cord or the like formed into a design substantially 90 raised from the surface of said felt and directly embedding in the surface of said web, whereby pronounced, permanent intaglio 95 markings will be formed in said web by said raised means while the web is carried by said felts and is being densified. 100

6. The method of marking a web of plastic material which comprises passing said web between carrying felts, at least one of which is provided on its face in contact with the web with raised markings, and gradually exerting increasing pressure upon said felts whereby the density of the web is increased and the raised markings become embedded in the web and leave pronounced, permanent markings indented in the face of the web. 105

7. The method of marking webs of plastic material which comprises securing strong, tough cord in the form of designs on that face of a carrying felt which comes in contact with the web, carrying the web upon said felt between press rolls to densify said web and to thoroughly embed the cord designs in the web, and after said web has been densified, removing it from said carrying felt, whereby said web will have pronounced, permanent, indented markings. 115

8. The method of marking newly formed webs of fiber board which comprises securing substantially raised characters upon that face of a carrying felt which comes in contact with the web, carrying the web upon said felt between means for gradually increasing 120 125 130

the density of the web and thoroughly embedding the raised characters in the surface of the web, removing the web from the felt, and drying said web, whereby said characters
5 will appear in reverse in said web as pronounced, permanent, indented markings.

9. The method of marking plastic webs of fiber board which comprises securing substantially raised characters upon the face of
10 a felt, bringing the face of said felt having the raised characters into intimate contact with the face of said web while still in plastic condition, exerting pressure upon said felt and web to densify the web and to thoroughly embed the raised characters in the surface thereof, and drying said web, whereby pronounced, permanent, indented markings will appear in the surface of said web.
15

Signed at Downingtown, Pennsylvania,
20 this 8th day of July, 1929.

JACOB EDGE.
